STOCKING

Harry A. Florsheim, New York, N. Y., assignor to Wisteria Hosiery Mills, Inc., Gastonia, N. C., a corporation of North Carolina

Application June 15, 1950, Serial No. 10,535

Term of patent 14 years

(Cl. D47—7)

To all whom it may concern:

Be it known that I, Harry A. Florsheim, a citizen of the United States, residing at 880 Fifth Avenue, New York, State of New York, have invented a new, original, and ornamental Design for a Stocking, of which the following is a specification, reference being had to the accompanying drawing, forming a part hereof.

I claim:

The ornamental design for a stocking, as shown.

HARRY A. FLORSHEIM.
